(57) **CLAIM**

The ornamental design for a disposable baby bib, as shown and described.

DESCRIPTION

FIG. 1 is an orthographic plan view of the disposable baby bib which is defined by a plurality of spacedly arrayed perforations within individual sheets of a roll of multiple interconnected individual sheets of disposable paper towels, showing our new design.

FIG. 2 is an orthographic plan view, similar to that of FIG. 1 showing a second contemplated embodiment of our disposable baby bib.

FIG. 3 is an orthographic plan view, similar to that of FIG. 1 and FIG. 2 showing a third contemplated embodiment of our disposable baby bib.

FIG. 4 is an orthographic plan view, similar to that of FIG. 1 and FIG. 2 and FIG. 3 showing a fourth contemplated embodiment of our disposable baby bib.

FIG. 5 is a perspective view of a roll of disposable paper towels, having multiple interconnected individual sheets, showing the disposable baby bib formed by a plurality of spacedly arrayed perforations in each disposable sheet; and, FIG. 6 is a perspective view of our disposable baby bib in use on a child sitting at a counter, the disposable baby bib formed in an individual sheet of disposable paper towels, having been separated from the roll of a multiple interconnected individual sheets of paper towels, and the neck opening formed along the defined spacedly arrayed perforations, and the neck opening flap folded forwardly.

The even dashed broken lines illustrating perforations on the surface of the disposable baby bib form part of the claimed design.

The broken line showing of a child sitting at a counter (FIG. 6) are for the purpose of illustrating environment of the claim and forms no part of the claimed design.

The dot-dash broken lines represent the boundary of the claimed design and forms no part of the claim.

The even dashed broken lines illustrating the disposable baby bib and roll of multiple interconnected individual

(Continued)

sheets of the roll represent portions of the disposable baby bib that form no part of the claimed design.
